SWITCH MECHANISM

Filed March 20, 1934

UNITED STATES PATENT OFFICE

2,068,701

SWITCH MECHANISM

Rudolf Popp, Valparaiso, Ind., assignor to McGill Manufacturing Company, Valparaiso, Ind., a corporation of Indiana

Application March 20, 1934, Serial No. 716,541

6 Claims. (Cl. 200—64)

My invention relates to switch mechanisms and more particularly to the small type of switch ordinarily employed in a canopy or in similar places where a small switch is required for controlling a lamp and other circuits.

An object of my invention is to provide a switch of the above character for a two-circuit control, such as for controlling two filament lamps wherein either one or both filaments may be cut in circuit or both cut out, and in which successive operations of the actuating button brings about the above control.

Another object of my invention is to provide a switch of the above character of the so-called three-way control and also known as a two-way switch adapted for control of a circuit from two points.

Another object of my invention is to provide a switch mechanism readily interchangeable or readily adaptable for assembly into either one of the two above types of switch mechanisms. The present invention is applied more particularly to a switch mechanism of the character shown in my prior application Serial No. 652,823, filed January 21, 1933, now Patent Number 1,974,054, issued September 18, 1934, although it is to be understood that there are features of my invention not limited to the specific mechanism referred to.

There are other objects to my invention and these will be apparent from a reading of the ensuing part of the specification and appended claims.

Referring to the drawing;

Figs. 1 to 9 show the two-circuit switch; and Figs. 10 to 15, the three-way switch.

Fig. 1 is a top plan view of a two-circuit switch mechanism with the top insulating plate removed;

Fig. 2 is a sectional view of Fig. 1;

Fig. 3 is a left end view of Fig. 1;

Fig. 4 is a top plan view of the switch of Fig. 1 but with the top plate and third contact in place;

Fig. 5 is a detailed view of the contact spider on the ratchet wheel;

Fig. 6 is a perspective view of the third contact;

Fig. 7 is a perspective view of a combination clamp and terminal for the third contact;

Fig. 8 is a detailed view of the top plate of the switch frame;

Fig. 9 is a diagrammatic view of a circuit controlled by the two-circuit switch of Figs. 1 to 8;

Fig. 10 is a top plan view similar to Fig. 1 but with a contact arranged for a three-way switch;

Fig. 11 is a front view of Fig. 10;

Fig. 12 is a right end view of Fig. 10;

Fig. 13 is a perspective view of the third contact of the switch;

Fig. 14 illustrates diagrammatically the contact mechanism of Fig. 10; and

Fig. 15 diagrammatically illustrates a circuit controlled by the three-way switch.

Referring now more in detail to the two-circuit switch of Figs. 1 to 9 and considering first the operation of the switch, as applied to a two filament lamp, as in Fig. 9, three contacts, A, B, and C are provided, adapted to be connected in various ways by the contact spider on the ratchet wheel. Connected to the contacts are two filaments of a lamp connected to the line or power circuit. With the switch in the position shown in Fig. 9, which corresponds to the position of the switch in Fig. 1, line contact C of the switch is off or dead. The first pull connects contacts C and A through the bridge with contact B off, lighting filament A. The next pull connects contacts C and B together with contact A off, thereby lighting filament B. The next pull connects all three contacts C, B, and A through the contact bridge thereby lighting both filaments. The next pull brings the contact bridge to a position similar to that shown in Fig. 9 with both filament contacts A and B disconnected because line contact C is dead. Successive pulls will then operate the switch the same as before. Thus we have a circuit control whereby the first pull connects one circuit, the next pull the other circuit, the next pull both circuits, and the next pull dead. Now, as to the switch mechanism of Figs. 1 to 8, a contact wheel 17 of insulating material is provided having an integral ratchet wheel adapted to be stepped ahead by successive operations of the tiltable lever 18 which pulls on the pawl 19 to advance the contact wheel step by step. In order to provide a two-circuit control, I apply a six-contact spider 20 having two sets of adjacently disposed contacts 21, each three in number and interposed dead spaces 22 between the sets, this bridge piece being applied to the contact wheel 17 so that the contact portions 21 lie in the teeth as indicated in Figs. 1 and 9. These six contact segments are all connected in common as shown in Fig. 5, and each segment 21 is preferably a separate section as I have found this cuts down the arcing. However, if desired, each set of three segments may be formed as a continuous peripheral contact the length of the three segments, as it is only necessary to effect continuous contact with a stationary contact for three steps, and a break for one step to effect the two circuit controls. Cooperating with the contact

wheel are the three contact brushes A, B and C, brushes B and C being mounted upon the terminal plates 23 and 24, and the third contact A mounted upon the frame top plate 25.

- 5 In order to permit of the interchangeable use of the switch mechanism, that is, so that it may be assembled as a two-circuit switch or a two-way switch, this third contact A is applied to the top plate by a terminal plate 26. To this end the 10 plate A is provided with a small opening 27 adapted to receive the tail 28 of the terminal plate 26, which tail piece also projects down through a hole 29 in the top plate and hooks underneath the plate as indicated in Fig. 2. The third contact A has a central opening 30 to clear the shaft of the ratchet wheel which extends into the center bearing 31 of the top plate, and contact A is also provided with a third hole 32 adapted to receive a boss on the lower part of the terminal 15 plate 26 so as to hold the parts together and prevent relative lateral movement. The contact 20 spring A has a downwardly projecting portion 34 which passes down through the slot 35 in the top plate and continues on into a laterally extending 25 brush portion 36 which contacts with the contact spider of the ratchet wheel.

In assembling the third contact A, it is applied to the top plate after which the tail piece 28 of the terminal plate is passed down through the 30 hole 27 of the contact A and then downwardly through the hole 29 in the top plate and then the terminal plate 26 is pivotally moved downwardly so that the front ear 37 passes down through the small slot 38 in the top plate, after 35 which this ear 37 is bent under the frame plate as indicated in Fig. 2 to hold the parts together, thereby holding the brush 36 of contact A in proper relation to the contact wheel.

With the switch thus assembled, the terminals 40 33, 23 and 24 are readily available for connecting the three brushes A, B and C respectively. The switch itself is inserted in the usual casing provided for this type of switch and the switch itself may be mounted in any suitable manner and 45 preferably by the threaded neck in a well known manner.

When the switch is used for controlling a two-filament lamp, it may be connected in circuit as shown in Fig. 9 so as to effect the independent 50 control of the two filaments or the lighting of both simultaneously, simply by successive pulls on the control lever.

Referring now to the three-way switch of Figs. 10 to 15 in this case, I substitute for the 55 six point contact wheel of Fig. 1, a standard four point contact wheel 17', leave the contacts B and C as in the two circuit switch of Fig. 1 and substitute a bridging contact A' adapted to engage a single contact of the wheel 17' at all times. 60 In other words, in this three-way switch the contact A' is always in contact with one of the four contact plates 21' but the contacts B and C are alternately switched in circuit. This contact A' for this reason has a longer contact arm 36' than 65 what is used in the first switch. Thus with the three-way switch in the position shown in Figs. 10 and 14, contact A' is contacting one segment 21' of the contact wheel and thus connected with contact B. Upon the first pull of the switch, the 70 contact wheel is advanced one point thereby connecting a contact 21' with the heel 36' of contact 36' and connecting C in circuit. Contact B however, is now resting upon a dead tooth of the contact wheel so that the circuit is connected 75 from A' to C only. The next pull of the switch

will advance the contact wheel one point and this time we are again connecting A' with contact B but now contact C is disconnected. Accordingly, as the switch is advanced step by step, the circuit is switched from contact A' back and forth between contacts B and C. A circuit for such use is diagrammatically illustrated in Fig. 15, and the contacts correspondingly marked. Thus assuming the lamp in the circuit is being controlled, as shown, the circuit is open. Upon 10 operation of one of the switches, the lamp is cut in circuit and may be cut out from the same switch or from the other one. In other words, we have the two point control for the lamp or for 15 any other circuit that might be included. 15

From the foregoing it will be seen that I have provided a small compact switch mechanism which by the use of only different contact wheels and different third contacts may be readily assembled for use as either a two-circuit switch 20 or a three-way switch.

What I claim as new and desire to protect by Letters Patent of the United States is:

1. A switch mechanism comprising a frame including upper and lower insulating plates, a 25 ratchet and contact wheel having peripheral contact segments thereon between the plates, a pair of stationary contacts for engagement with the contact segments, a third stationary contact positioned upon one of the insulating plates and 30 having a contact arm extending laterally between the plates and resting upon the peripheral edge of the contact wheel, and a terminal plate having a tail piece extending through the third contact and frame plate and an ear passing through 35 and bent over the bottom of the frame plate to hold the third contact on the insulating plate.

2. A switch mechanism comprising a frame including upper and lower insulating plates, with 40 one of said plates having a slot extending inwardly from one edge, a ratchet and contact wheel having peripheral contact segments thereon between a pair of stationary contacts for engagement with the contact segments, a third stationary contact positioned upon the slotted insulating plate and having a contact arm extending laterally between the plates and resting upon the peripheral edge of the contact wheel, with said third contact having a connecting portion 45 extending upwardly from said contact arm and through said slot of the insulating plate to lie wholly inside the outer edge of said plate, and a terminal plate in engagement with said third contact for maintaining said contact on said insulating plate. 55

3. A switch mechanism comprising a frame including upper and lower insulating plates, a toothed insulating wheel rotatably mounted between the plates, a contact segment member carried on said wheel with the contact segments positioned on the teeth of said wheel, a pair of oppositely disposed stationary contacts mounted between the plates and resting upon the contact segment portion on said wheel, a third stationary contact member having a mounting portion supported on one of said insulating plates and a contact portion engaging said contact segment portion on said wheel, with an intermediate connecting portion for said contact member extending through said one insulating plate, and a terminal member on said one insulating plate engaging said third stationary contact member at the mounting portion to rigidly support said contact on said one insulating plate, with said mechanism such that by changing only the contact 7 7

- segment member and the third stationary contact member either a two-circuit switch or a three-way switch is provided.
4. A two-circuit switch comprising a frame including a pair of spaced apart insulating plates, an eight tooth insulating wheel rotatably mounted between the plates, a six-segment contact member carried on said wheel with said segments positioned on the teeth of said wheel, a pair of oppositely disposed stationary contacts mounted between the plates and resting upon the contact segment portion on said wheel, a third stationary one-piece contact member having a mounting portion supported on one of said insulating plates and a contact portion of such a shape and positioned as to lie over two adjacent teeth of said wheel to always engage a contact segment of said four-segment contact member, and said third stationary contact having a connecting portion between the mounting and contact portions extending through said one insulating plate, and a 10 terminal member on said one insulating plate for clamping said mounting portion of said third contact member on said one insulating plate.
5. A switch mechanism comprising a frame including upper and lower insulating plates and a pair of terminal posts connecting the plates, a ratchet and contact wheel having peripheral contact segments thereon, a pair of stationary contacts one supported by each post for engagement with the contact segments, and a third contact stamped from a sheet of metal and supported solely by one of the frame plates and extending between the frame plates for engagement with the contact segments, a terminal plate having a tail piece extending through the third contact and frame plate, and an ear bent around the frame plate, and a terminal screw threaded thereon, said terminal plate clamping said third contact against said frame plate, and said segments and contacts being disposed to effect electrical connections between different contacts by advancement of the contact wheel.
6. A three way electric switch mechanism comprising a frame having a pair of spaced apart insulating plates, an eight tooth insulating wheel rotatably mounted between the plates, a four-segment contact member carried on said wheel with said segments positioned on the teeth of said wheel with a blank tooth and a segment covered tooth alternating around the wheel, a pair of oppositely disposed stationary contacts mounted between the plates and resting upon the contact segment portion on said wheel, a third stationary

one-piece contact member having a mounting portion supported on one of said insulating plates and a contact portion extending laterally between said plates and of such a shape and positioned as to lie over two adjacent teeth of said wheel to always engage a contact segment of said four-segment contact member, and said third stationary contact having a connecting portion between the mounting and contact portions extending through said one insulating plate, and a 10 terminal member on said one insulating plate for clamping said mounting portion of said third contact member on said one insulating plate.

7. A switch mechanism comprising a frame including upper and lower insulating plates and a pair of terminal posts connecting the plates, a ratchet and contact wheel having peripheral contact segments thereon, a pair of stationary contacts one supported by each post for engagement with the contact segments, and a third contact stamped from a sheet of metal and supported solely by one of the frame plates and extending between the frame plates for engagement with the contact segments, a terminal plate having a tail piece extending through the third contact and frame plate, and an ear bent around the frame plate, and a terminal screw threaded thereon, said terminal plate clamping said third contact against said frame plate, and said segments and contacts being disposed to effect electrical connections between different contacts by advancement of the contact wheel.

RUDOLF POPP.
